Andrd O'rense,

UNITED STATES PATENT OFFICE.

ANDREW OVEREND, OF PHILADELPHIA, PENNSYLVANIA.

PRINTER'S FRISKET.

Specification of Letters Patent No. 11,072, dated June 13, 1854.

To all whom it may concern:

Be it known that I, ANDREW OVEREND, of the city of Philadelphia and State of Pennsylvania, have invented a new and useful Improvement in the Construction of Printers' Friskets; and I do hereby declare that the following is a full, clear, and exact description of the same, reference being had to the accompanying drawings, in which—

10 Figure 1 is a view of the upper side of my improved frisket, and Fig. 2 a view of the opposite side of the same.

Friskets are used by book and job printers for the purpose of preventing the margin of the paper which surrounds each page of printed matter from being stained or marked while the impression is being made. They are usually constructed of a metallic frame which is covered by layers of paper pasted together or thick canvass or muslin. An impression of the page or printed matter is then taken on this covering and the parts printed upon are cut out, thus leaving a frame work of thick paper or canvas to 20 cover and protect the margins of the printed matter. The process of preparing a frisket in this manner occupies from one to two hours and involves the expense of a fresh paper or muslin covering on each 30 occasion that the sizes of the pages or forms are changed.

My improvement consists in constructing the frisket of a wrought iron or metallic frame notched along its outer sides like saw teeth and then stretching longitudinally and transversely across the frame elastic strips having at each end a clamp. These clamps are indented and can be slid along the sides of the frisket frame or they will remain 40 permanently in any position in which they may be placed. By this means I form a movable barred frisket frame which can be altered or adjusted to varied forms of pages in from 3 to 5 minutes without involving 45 any loss of material.

To enable others skilled in the art to make and use my improvement I proceed to describe its construction and operation.

A B C D in Figs. 1 and 2 represent respectively the back and front view of my frisket frame. It is usually made of wrought iron—is about one inch on the face and one eighth of an inch thick. The outer edge of each side of the frame is beveled down on 55 the front at an angle of about 40° as shown

in Fig. 2. On this beveled edge a series of saw teeth *e e e e* are notched with a file as close together as ordinary saw teeth. These teeth are notched on the edges of each of the four sides of the frisket frame as shown 60 in Figs. 1 and 2. The movable bars M, N, M', N', &c., and O, P, O', P', &c., are formed of india rubber webbing or other similar elastic material and are attached at each extremity by rivets or other convenient mode 65 to the flat hooks or clamps H and I &c. H', I' &c., and F and G &c. These flat hooks or clamps are made of sheet tin or iron and are bent over at their extremity so as to correspond with the bevels in the edges of 70 the frisket frame. These hooks or clamps are slightly notched or indented at their outer extremity as shown at K, K, K, K, Theses mall notches *k* fit into the indentations of the saw teeth *e e e* and prevent the 75 elastic bars slipping laterally. The elastic bars are made just long enough to extend from side to side when moderately stretched. If they be stretched a little more then the bars and clamps can be slid or moved to any 80 desired part of the frame. The teeth *e e e* in each side of the frame are precisely opposite to corresponding teeth on the opposite side of the frame. The movable elastic bars are made of about the width of the ordinary margin between the pages of a book or several sets of bars of various widths can be made for each frame and used as occasion may require. It will be evident that 85 by stretching the bars O, P, O', P', &c., 90 longitudinally across the frame and hooking them at H, I, H', I', &c., and by stretching transversely the bars M, N, M', N', &c., in the same manner a frisket can be quickly formed leaving the spaces L L L, &c., for 95 the printed impression of any desired size—while at the same time the elastic bars will effectually protect the marginal spaces on the paper from being soiled.

Having thus described my improvement, 100 what I claim as my invention and desire to secure by Letters Patent is—

The construction of movable barred frisket frames by the combination of elastic bars clamps and toothed frisket frame arranged and operating as herein described.

ANDW. OVEREND.
